UNITED STATES PATENT OFFICE.

FRANK RIEBER, OF SAN FRANCISCO, CALIFORNIA, ASSIGNOR TO THE RIEBER LABORATORIES, OF SAN FRANCISCO, CALIFORNIA, A CORPORATION OF CALIFORNIA.

ELECTRIC CONTROL SYSTEM.

1,225,860.

Specification of Letters Patent. Patented May 15, 1917.

Application filed August 17, 1916. Serial No. 115,414.

To all whom it may concern:

Be it known that I, FRANK RIEBER, a citizen of the United States, and a resident of the city and county of San Francisco, State 5 of California, have invented a certain new and useful Electric Control System, of which the following is a specification.

The invention relates to electric control systems and particularly to control systems 10 for Röntgen fluoroscopic apparatus.

An object of the invention is to provide a simple means for simultaneously controlling the illumination of a fluoroscopic room and the energizing of the Röntgen tube.

15 Röntgen-ray apparatus for fluoroscopic purposes is commonly placed in a dark room in which the physician or operator must remain until satisfactory retinal accommodation is obtained to render the eyes sufficiently 20 sensitive to conduct examination.

For practical reasons this room cannot be made absolutely dark. It is necessary, in order that the patient and operator may find their way about, to maintain the room normally 25 in a state of faint illumination, preferably with red or reddish light. During the actual examination even this illumination is not permissible and the light must be turned off in some manner.

30 To accomplish this, various switches have been devised which operate to simultaneously interrupt the lighting circuit and actuate the Röntgen-ray apparatus. Such switches have two sets of electrical connections 35 in mechanical combination, and are connected with two supply circuits, thereby becoming unnecessarily complex to construct and connect.

In accordance with my invention I have 40 provided a control circuit of such nature that a simple switch containing only one set of electrical contacts is used to control simultaneously the room and tube illumination.

The invention possesses other advantageous 45 features, which, with the foregoing, will be set forth at length in the following description where I shall outline in full that form of the invention which I have selected for illustration in the drawing accompanying and forming part of the present specification. In the drawing I have shown only one specific form of my invention but it is to be understood that I do not limit myself to such form.

The drawing is a diagrammatic representation of the control system of my invention.

The Röntgen tube 2 is energized from the supply circuit 3—4, through the transformer 5. Arranged in the circuit 3—4 is the usual controlling rheostat 6 for the tube 60 circuit. Arranged in the supply circuit is a switch 7, around which is shunted the lamp 8 which provides illumination for the fluoroscopic room. When the switch 7 is open the lamp is in series with the transformer and 65 when the switch is closed the lamp circuit is short circuited. The resistance of the lamp may be very high in view of the low candle power required and this high resistance operates when the switch is open to allow only 70 a very small amount of current to flow through the transformer, the current being such that the Röntgen tube is not energized. By closing the switch, the lamp is short circuited and the normal current is applied to 75 the transformer. In practice the switch 7 may advantageously take the form of a heavily constructed push button and may be arranged to be operated either by the hand or foot of the operator.

80 A further advantage of my invention is that the lamp 8 operates to a certain extent to quench the spark formed at the switch 7, thereby permitting the safe use of a lightly constructed switch.

85 I claim:

1. The combination with a Röntgen-ray tube and a circuit therefor, of a high resistance lamp in series in said circuit and means for shortcircuiting the lamp and causing the 90 tube to be energized.

2. The combination with a transformer of a supply circuit connected to the primary of the transformer, a Röntgen ray tube connected to the secondary, a high resistance 95 lamp in series with the primary and adapted to limit the current therethrough and to illuminate the room in which the tube is arranged and a switch for shortcircuiting said lamp.

100 In testimony whereof, I have hereunto set my hand at San Francisco, California, this 10th day of August, 1916.

FRANK RIEBER.

In presence of—
H. G. PROST.
